(57) **CLAIM**

The ornamental design for a golf device, as shown and described.

DESCRIPTION

FIG. 1 is a top side elevation view of the golf device;

FIG. 2 is a bottom side elevation view thereof;

FIG. 3 is a front elevation view thereof;

FIG. 4 is a right side elevation view thereof;

FIG. 5 is a left side elevation view thereof;

FIG. 6 is a front-top perspective view thereof; and,

FIG. 7 is a rear-bottom perspective view thereof.

The broken lines in the drawings illustrate portions of the golf device that form no part of the claimed design.

1 Claim, 7 Drawing Sheets
